(57) **CLAIM**

I claim a new ornamental design for an earring, as shown and described.

DESCRIPTION

FIG. 1 is a perspective view of an earring showing my new design;

FIG. 2 is a front elevational view of the earring of FIG. 1; FIG. 3 is a rear elevational view of the earring of FIG. 1, FIG. 4 is a left side elevational view of the earring of FIG. 1; the right side elevational view of the earring of FIG. 1 is a mirror image of FIG. 4;

FIG. 5 is a top plan view of the earring of FIG. 1; and, FIG. 6 is a bottom plan view of the earring of FIG. 1. The broken lines shown on the drawings represent portions of the earring which form no part of the claimed design.

1 Claim, 3 Drawing Sheets

FIG. 1**FIG. 2**

FIG. 5

FIG. 6
